UNITED STATES PATENT OFFICE.

DODSON HASLUP, OF GRAFTON, WEST VIRGINIA.

ORNAMENTAL DISPLAY DEVICE.

Application filed October 30, 1923. Serial No. 671,682.

To all whom it may concern:

Be it known that I, DODSON HASLUP, a citizen of the United States, residing at Grafton, in the county of Taylor and State 5 of West Virginia, have invented certain new and useful Improvements in Ornamental Display Devices, of which the following is a full, clear, and exact description.

My invention relates to a flag holder and 10 wind wheel to be mounted on the filling nozzle of automobile radiators and the like, and has for its object the provision of a simple and inexpensive support or clamp therefor.

A further object of the invention resides 15 in combining with the main support a bearing for the wind wheel and a bracket for displaying flags, a banner and the like.

Other objects and advantages of the invention will be apparent from the following 20 description when taken in connection with the accompanying drawings, in which,

Figure 1 is a front elevation of the device.

Figure 2 is a plan view thereof with the flags removed.

Figure 3 is a fragmentary section taken 25 on the line 3—3 of Figure 2.

Figure 4 is a section taken on line 4—4 of Figure 2, and

Figure 5 is a perspective view of the forward portion of the supporting bracket.

Referring to the drawings more in detail the numeral 1, indicates the usual automobile radiator nozzle to which the device is attached, although it will be understood that 35 my device may be attached to any other appropriate support. The clamp which supports the display elements may be made of wire or the like and comprises the two legs 2—2 and base 3, as clearly shown in Figures

40 2 and 5. The legs and base, 2 and 3 respectively, are bent up from a single piece of material and the former are provided with the curved ends 4—4 for engaging a suitable support. The legs 2—2 are further provided

45 with the aligned loop portions 5—5 which receive a bolt and adjusting nut 6 and 7 respectively. By this construction it will be seen that the clamp may be readily secured in place; a brace 8 being provided to prevent bending of the legs 2 when clamp is being secured by means of the bolt and nut 6 and 7.

On the forward end of the clamp is mounted a bracket formed of sheet metal. 50 This bracket may be stamped up from a pair

of blanks, and comprises a base portion 9 and vertically extending plates 10 and 11. The base 9 is notched to provide flanges 12 and 13 which are bent around the legs and base of the clamp so as to firmly connect 60 the bracket therewith. The plate 10 is provided with a base 10' bolted onto the base 9 as indicated in Figures 2 and 5.

A wind wheel 14 having the usual blades 15 is provided with a boss 16 and corrugated 65 flange 17 on its rear face. The wind wheel 14 is mounted for rotation in the bracket by means of shaft 18 which extends through wind wheel 14, boss 18 and the plates 10 and 11. The corrugated flange 17 in addition to reinforcing the wind wheel provides sockets in which flagstaffs 19 may be positioned.

Bolted to, but spaced from the plate 11 is an additional plate 20 which cooperates 70 with the plate 11 to provide a clamp for holding flagstaffs 21—21. A banner 22, carrying advertising matter or the like 23, may be secured to the flagstaffs 21 and will aid in supporting these members in proper 75 position.

In operation of the device, it will be understood that the same may be secured to an automobile or other vehicle and that it may be employed with or without the 80 flags 19 and with or without the flags 21.

From the foregoing description taken in connection with the accompanying drawings it will be seen that I have provided a neat and attractive display device which may be 85 readily attached to a support without liability of marring the latter, and which may be almost entirely constructed by stamping from sheet material.

In accordance with the patent statutes, 90 I have described what I now believe to be the best embodiment of the invention, but I do not wish to be understood thereby as limiting myself or the scope of the invention, as many changes and modifications may 95 be made without departing from the spirit of the invention; all such I aim to include in the scope of the appended claims.

What I claim as new and desire to secure by Letters Patent is:

1. In a device of the class described, an 100 adjustable clamp adapted to be secured to a support, a bracket secured to one end of the clamp, a wind wheel mounted for rotation in said bracket, and a plate spaced from 110

said bracket and forming therewith a clamp for flag staffs.

2. In a device of the class described, a clamp adapted to be secured to a support, a bracket secured to one end of the clamp and including a pair of vertically extending plates, a wind wheel having its shaft mounted in said plates, and an additional plate spaced from one of said first mentioned

plates and forming therewith a clamp for 10 flag staffs.

3. In a device of the class described, a wind wheel, a plate concentrically arranged on the wind wheel, said plate provided with one or more corrugations cooperating with 15 said wind wheel to form sockets for the reception of flag staffs.

DODSON HASLUP.
